Inventor
Jas. Ashworth,

E.W. Anderson,

UNITED STATES PATENT OFFICE.

JAMES ASHWORTH, OF DENVER, COLORADO.

STOVE FOR CONSUMING STRAW, HAY, &c.

SPECIFICATION forming part of Letters Patent No. 430,912, dated June 24, 1890.

Application filed September 30, 1889. Serial No. 325,545. (No model.)

To all whom it may concern:

Be it known that I, JAMES ASHWORTH, a citizen of the United States, and a resident of Denver, in the county of Arapahoe and State 5 of Colorado, have invented certain new and useful Improvements in Stoves for Consuming Straw, Hay, &c.; and I do declare the following to be a full, clear, and exact description of the invention, such as will enable others 10 skilled in the art to which it appertains to make and use the same, reference being had to the accompanying drawings, and to letters of reference marked thereon, which form a part of this specification.

15 Figure 1 of the drawings is a representation of a front view of this invention in perspective. Fig. 2 is a vertical sectional view. Figs. 3, 4, and 5 are detail views. Fig. 6 is a detail plan view disclosing the valve d' .

20 This invention relates to certain improvements in that class of stoves more especially adapted for burning straw, hay, hemp, flax, corn stalks and cobs, cane-pulp, weeds, and refuse suitable for fuel; and it consists of the 25 novel combination and construction of parts, as will fully appear from the following description and accompanying illustration.

In carrying out my invention I employ a base A, suitably supported upon legs, a removable magazine, drum, or cylinder B, and a cap or dome C, the drum or magazine being mounted upon the base and the cap or dome upon the drum or magazine. The base A has an ash-pan chamber a' , in the front part of 35 which is a series of draft-openings b , which are opened and closed as required by a slide or valve b' , having a series of registering openings in it, and adjusted upon the said ash-pan chamber front between cleats or flanges 40 thereon. This slide has a suitable knob b'' for its manipulation. A semicircular cleat or flange c is cast upon the base A at its rear side, while upon the front part of the drum or magazine is secured a bar or cleat c' , meeting

45 the cleat or flange c end to end, and which jointly inclose or cover the lower or base edge of the said drum or magazine. The drum or magazine B has in its bottom a central aperture or passage d for the admission of air or draft necessary for combustion to the contents of the drum or magazine. This aper-

ture or passage is adapted to be closed to prevent the accidental escape of any remaining fuel, when it is desired to remove the drum or magazine for refilling, by means of a valve or 55 slide d' , pivoted to the bottom of the latter, and having a rod or handle d^2 extending out through a slot d^3 in the side of the drum or magazine. The drum B has at the back near its bottom a valved or slide-covered opening 60 e to further promote combustion. To opposite points upon the sides of the drum or magazine B are secured hand-holds or handles f for the convenient lifting and carrying of the latter in effecting its removal and replacement. The drum or magazine has applied to its upper end an annular flange or ring h , which is formed with opposite L-shaped slots or notches i extending through the top and inner side of the annulus or flange, and which 70 receives projections or studs i' i' , projecting from a rim i^2 on the under side of the cap or dome, and thus provide for detachably connecting the drum or dome thereto.

D D are retaining-rods which are let into 75 and are secured in sockets j j on the base A at their lower ends, while their upper ends are similarly secured or connected, as at k , to the ring k' , resting just above and closely to the top edge of the drum or magazine, the 80 drum or magazine being removable from between the base and cap or dome without disturbing the latter. The base-rods do not extend entirely around the base and cap or dome, but sufficient space is left between the 85 front ones to permit the removal of the drum. The cap or dome has attached to it a smoke-pipe, and in its lower portion a circular series of air passages or apertures, and over the same is adjusted a sliding band or slide l , having a series of registering openings to open and close the said openings as required, said band or slide having a knob for its adjustment or movement.

In practice I provide a plurality of drums 95 or magazines, having one filled and ready to displace the one in which the process of combustion is going on, as soon as its contents are consumed, the latter then being removed and refilled, as above intimated. It is obvious 100 that by the requisite adjustment or opening and closing of the valve-openings alternately

in opposite ends of the drum or magazine the process of combustion can be conducted so as to consume the fuel at either end or both ends.

Having described this invention, what I claim, and desire to secure by Letters Patent, is—

1. The stove having a base, a removable drum or magazine, and a cap or dome, said base having upon its rear surface a fixed flange or cleat, and the drum having upon its front surface a similar cleat or clamp-bar arranged end to end to the aforesaid cleat or flange, substantially as set forth.
2. The stove having a base, a removable drum or magazine, and a cap or dome, said drum or magazine having a band or annulus provided in its top and inner wall with opposite notches or slots receiving projections or studs on a rim of the dome or cap, substantially as set forth.

2. The stove having a base, a removable drum or magazine, and a cap or dome, said drum or magazine having a band or annulus provided in its top and inner wall with opposite notches or slots receiving projections or studs on a rim of the dome or cap, substantially as set forth.

In testimony whereof I affix my signature in presence of two witnesses.

JAMES ASHWORTH.
